[57] CLAIM

The ornamental design for a louvered boat vent, substantially as shown and described.

DESCRIPTION

FIG. 1 is a top perspective view of a louvered boat vent showing my new design;
FIG. 2 is a top plan view thereof;
FIG. 3 is a bottom plan view thereof;
FIG. 4 is a side elevational view of FIG. 2;
FIG. 5 is an end elevational view of the right end of FIG. 6;
FIG. 6 is a cross-sectional view taken on the line 6—6 of FIG. 2;
FIG. 7 is a cross-sectional view taken on the line 7—7 of FIG. 2;
FIG. 8 is a partial cross-sectional view taken along the line 8—8 of FIG. 3;
FIG. 9 is a partial cross-sectional view taken along the plane 9—9 of FIG. 3;
FIG. 10 is an end elevation view of the left end of FIG. 6.
